ELECTROMAGNETIC DEVICE AND CIRCUITS
FOR OPERATING THE SAME

Samuel Karasick, Mount Vernon, N. Y.

Application September 26, 1933, Serial No. 691,048

12 Claims. (Cl. 175—181)

This invention relates to combined electromagnetic holding devices and demagnetizers as well as to the circuits for operating the same.

In holding devices or chucks of this character, it has been customary to provide for direct current operation, and to effect demagnetization of the work on the chuck by reversing the direction of flow of current through the chuck by the use of a reversing switch, but, even by the most careful manipulation of the reversing switch only partial demagnetization of the work could be effected. Where an electromagnetic chuck was used to hold work including ferromagnetic pieces, the residual magnetism of the work caused it to adhere tightly to the chuck even through the chuck windings had been deenergized and as a result the work could be removed only with great difficulty unless the reversing switch was carefully manipulated to effect a partial demagnetization. This effect was especially troublesome if the work was of hardened steel.

Furthermore, it has never been practicable to secure any great degree of demagnetization by this method of manual operation of a reversing switch and where the work requires complete demagnetization, it has been necessary to provide a separate device known as a demagnetizer for this purpose.

The present invention has for its purpose the construction and arrangement of an electromagnetic chuck energized either by direct current or by alternating current whereby the work may be firmly held by direct current and be completely demagnetized by alternating current. This has not been commercially practical with chucks of the type heretofore known owing to the presence of closed loops of conducting material surrounding each pole of the chuck. Such loops have acted as short-circuited transformer windings and have effectively prevented any substantial amount of alternating magnetic flux from issuing from the poles of the chuck and passing through the work.

It is also a purpose of this invention to provide a magnetic device which is simple to assemble, inexpensive to manufacture and reliable in operation alternatively as a chuck and as demagnetizer. Other features of this invention will appear from the following description of a preferred form thereof, together with the appended claims.

In the drawing, Fig. 1 represents a perspective view of a preferred form of the invention with a portion thereof broken away to show the internal arrangement of the several parts; Fig. 2 is a transverse cross section of the cover plate shown

in Fig. 1; Fig. 3 is a perspective view of a modified form of cover plate and Fig. 4 is a circuit arrangement including switching means by which the device of Fig. 1 can be operated either as a holding device or as a demagnetizer.

Referring to Figure 1 of the drawing, the numeral 1 generally designates a core. This core is built up of a plurality of laminae each of which is a stamping from any suitable ferromagnetic material in sheet form, such as Norway iron, having a body portion 2 provided with a series of integral uprights or core elements 3 and extensions terminating in lugs 4. These laminae are first shellacked or enameled and then fastened together in any well-known manner, such as by rivets, to form an integral structure. The core 1 when thus assembled is placed in a suitable mold or support and a base 5 of aluminum or other suitable material is molded about the core 1 with the lugs 4 of the core engaged by lugs 6 which are cast integral with the base. When the base and assembled core have thus been made, each of the uprights or core elements is provided with a spool 7 provided with a coil or helical winding of the type well-known in the art, adapted to produce a magnetic flux in the said core when electric current flows through the mentioned winding. A suitable circuit arrangement for energizing these windings will be hereinafter referred to.

The chuck in this form is provided with a face plate on which the work to be held rests and which prevents dust or moisture from entering the core or coils of the device. This face plate is made up of a frame 8 and a series of pole pieces 9—9, each polepiece being separated from the others and from the frame 8 as will be further described. These polepieces, like the core, are also constructed of shellacked or enameled laminae and are held together by rivets 10 while the lateral surface of the polepieces as well as the opposing inner surface of the frame, are provided with notches 11 which cooperate in the manner to be described.

In assembling the face plate the frame 8 is placed on a level surface and the pole pieces 9 are located and tightly held within the frame 8 with a separation between adjacent polepieces and also between the polepieces and the frame as indicated in Fig. 1. When thus arranged, a suitable plastic non-conducting material 12 such as a synthetic resin or a phenol condensation material, is introduced under proper heat and pressure to completely fill all the spaces between the polepieces as well as between the polepieces and the frame. When this material has hardened, it

engages the notches 11 of the frame and pole-pieces to constitute an integral face plate which can be screwed or otherwise fastened to the base 5. The use of the nonconducting material 12 eliminates the closed conducting loops about the pole-piece of the chuck so that the alternating flux can pass through the work and thereby demagnetize it thoroughly.

In Fig. 3 there is disclosed a slightly modified form of face plate for the chuck in which the adjacent pole-pieces 9a are in dove-tailed relation but the several pole-pieces 9a and the frame 8 are separated from one another by nonconducting material 12. Otherwise the construction of the face plate is the same as that disclosed in Figs. 1 and 2.

In Fig. 4 there is disclosed a circuit arrangement whereby the devices of Figs. 1, 2 and 3 can be utilized either as a chuck or as a demagnetizer, in which arrangement reference character 21 represents a source of alternating current, such as the usual 115 or 230 volt alternating current power service supplied by a commercial power company. This source is connected over conductors 22 and 23 to terminals 24 and 25 of the primary winding 26 of a power transformer under the control of a manual switch 21. This transformer is provided with a secondary winding 28 having end terminals 29 and 30 as well as a center tap terminal 31 while the portion of the secondary winding between terminals 30 and 31 is further provided with a mid-tap terminal 32. In addition to the secondary winding, the transformer has a tertiary winding 33 with end terminals 34 and 35, and also with the center-tap terminal 36. This tertiary winding serves to energize the cathodes of the rectifier tubes 37 and 38 of the two-element gas-filled high-current type which operate in the manner to be described, as a full wave rectifier. A four-pole double-throw switch 39 is provided so that either the direct current output of the double-halfwave or full wave rectifier or else the alternating voltage across the entire secondary winding 28 of the transformer can be connected alternatively at will to the magnetic chuck C.

In describing the operation of the circuit network of Fig. 4, it will first be assumed that switch 39 is closed to its lefthand or "hold" position. Let it be further assumed that at the given instant, terminal 31 of the secondary transformer winding 28 is positive with respect to terminal 32 thereof. Current will then flow from terminal 31 through conductor 40 to switch blade 42 of switch 39, contact 46 and thence to the anode 48 of rectifier tube 38. Since this anode is now positive, an arc will strike and current will flow through this arc to the cathode 49 and over conductors 50 and 51 to the terminals 34 and 35 of the tertiary or filament winding of the transformer and thence from terminal 36 over conductor 52 to terminal 53 of the chuck, over conductor 54 through coils 56, 58, 60, 62 and 64 in parallel to conductor 65 and through coils 55, 57, 59, 61 and 63 of the chuck C to conductor 66 and to terminal 67 of the chuck. From terminal 67 current will flow through conductor 68 and blade 44 of switch 39, contact 47 and over conductor 69 to terminal 32 of the transformer. However, on the next half cycle terminal 30 of transformer is positive with respect to terminal 32 so that current will flow from terminal 30 through conductor 71 to blade 41 of switch 39, thence to contact 45 and through conductor 70 to the anode 71 of tube 37. Since this anode is now positive,

current will flow across the arc which strikes to the cathode 72 of the tube and as before to conductors 50 and 51. The remainder of the circuit which includes the energizing coils and which terminates at the terminal 32 of the transformer is the same as that which has been previously disclosed. In this manner the chuck is energized by rectified alternating current, whereby a high intensity unidirectional flux is produced in the core extensions and a work piece thereon.

The term "high intensity" as here used means flux densities of approximately the value required to reach or pass moderately beyond the knee of the saturation curve in the magnetic circuit of the chuck, and the work held thereon.

It has been found that the inductance of energizing coils of the chuck is sufficient to filter out ripples in the rectified current thus supplied, to such an extent that no filter condensers or additional filter reactors are needed.

If now it is desired to demagnetize the chuck or any work thereon, switch 39 is thrown to the right hand position. This opens the anode circuits of the rectifier tubes 37, 38 at the same time the load circuit through the chuck is opened, avoiding the danger of a tube flashover, due to the high surge voltage developed when the chuck circuit is opened. Alternating current will now flow from terminal 29 of transformer over conductor 75 to switch blade 43, thence to contact 30 14 which is connected to terminal 53 of the chuck. From terminal 53 current will flow over conductor 54 through coils 56, 58, 60, 62 and 64 in parallel, to conductor 65 and to terminal 16 which is connected to contact 73 of switch 39. From contact 73 current flows to switch blade 41 through conductor 77 to terminal 30 of the transformer. It should be pointed out that the alternating current voltage applied to the chuck is at least four times the rectified direct or pulsating output voltage, neglecting the arc drop in tubes 37 and 38. Also only half the coils of the chuck C are in circuit, corresponding to the fact that the alternating current impedance of a winding of the chuck at 60 cycles is about four to five times its direct current resistance. It has been found that to secure efficient demagnetizing action, the root mean square value of the alternating current in the chuck should be about equal to the direct current used in the same winding to hold the work.

While a particular embodiment of the invention has been described, it will be understood that my invention is capable of still further modification and that this application is intended to cover any variations, uses, or adaptations of my invention falling within the scope of the invention and the limits of the appended claims.

What I claim is:

1. An electromagnetic holding and demagnetizing device comprising a plurality of flux producing units, a source of alternating current, a source of direct current, and means operated at will for connecting a plurality of units to said direct current source and for connecting alternatively a portion only of said last-mentioned units to said alternating current source.

2. An electromagnetic holding and demagnetizing device comprising a plurality of flux producing units, a source of alternating current, a rectifier connected to an alternating current source, and means operated at will for connecting a plurality of said units to the output of said rectifier or to connect a lesser number of said last-

mentioned units to said alternating current source.

3. In a system of the class described, an electromagnetic chuck having a plurality of core extensions each provided with a coil, a pair of conductors connecting the coils on alternate extensions into one group, a pair of conductors connecting the remaining coils in a second group, a source of alternating current, a source of pulsating direct current, means for connecting said pairs of conductors and coils connected thereto to said direct current source and alternately to connect one of said groups of coils to said source of alternating current, the alternating voltage applied to said last-mentioned group of coils being a multiple of the direct current voltage applied to both groups of coils.

4. In a system of the class described, an electromagnetic chuck having a plurality of core extensions each provided with a coil, said coils being arranged into at least two groups with the coils of each group connected in multiple, a source of alternating current, a source of pulsating direct current, means for connecting said groups of coils in series to said direct current source and alternately to connect one of said groups of coils to said source of alternating current.

5. In a system of the class described, an electromagnetic chuck having a plurality of core extensions, means for producing a high intensity unidirectional flux in the said core extensions and in a work piece held thereby, and selectively operable means for producing at will in said core extensions and said piece, an alternating flux of at least the same effective intensity as said unidirectional flux and at frequencies in the commercial power range.

6. An electromagnetic chuck comprising magnetic circuit means for establishing a high intensity unidirectional magnetic field for holding magnetizable material, and selectively controlled means including at least a portion of said first means for establishing an alternating magnetic field of an intensity approximately equal to said unidirectional magnetic field to substantially demagnetize said material, said alternating field having a commercial power frequency.

7. In a magnetic work holder, a support having a work holding surface, magnetic pole areas terminating in said surface, a source of unidirectional current, coils associated with pole areas, means to introduce unidirectional current into said coils from said source to energize said pole areas with positive pole areas interspaced among negative pole areas, a source of alternating current of commercial power supply frequencies, and means for disconnecting said coils from said unidirectional current source and for introducing alternating current from said alternating current source into certain of said coils arranged to afford an alternating current therein having an effective (root-mean-square) value approximately equal to the value of the direct current applied to said coils.

8. In combination, a combined magnetic holding and demagnetizing device, a commercial alternating current source for operating said device, said device comprising a core having core elements, at least a portion of said elements being each equipped with a coil, the impedance of which at the frequency of said source being several times as great as the direct current resistance thereof, a first circuit including certain of said coils and connectible to said alternating

current source, a second circuit connectible to said alternating current source and including rectifying means for supplying rectified current to certain of said coils, a transformer connected in one of said circuits, said transformer having such a transformation ratio that the total electromotive force in one of said circuits is materially greater than that in the other circuit, and means effective at will for connecting either of said circuits to said alternating current source. 10

9. In combination, a combined magnetic holding and demagnetizing device, a commercial alternating current source for operating said device, said device comprising a core having core elements equipped with coils, the impedance of which at the frequency of said source being several times as great as the direct current resistance thereof, a first circuit including certain of said coils and connectible to said alternating current source, a second circuit connectible to said alternating current source and including rectifying means for supplying rectified current to certain of said coils, transformer means in said circuits, said transformer means having such transformation ratios that the electromotive force in one of said circuits is materially greater than that in the other circuit, and means effective at will for connecting either of said circuits to said alternating current source.

10. In combination, a combined magnetic holding and demagnetizing device, a commercial alternating current source for operating said device, said device comprising a core having core elements equipped with coils, the impedance of which at the frequency of said source being several times as great as the direct current resistance thereof, a first circuit including certain of said coils and connectible to said alternating current source, a second circuit connectible to said alternating current source and including rectifying means for supplying rectified current to certain of said coils, the inductance of the coils in said first circuit being materially less than the inductance of the coils in said second circuit, a transformer connected in one of said circuits, said transformer having such a transformation ratio that the total electromotive force in one of said circuits is materially greater than that in the other circuit, and means effective at will for connecting either of said circuits to said alternating current source. 30

11. In combination, a combined magnetic holding and demagnetizing device, a commercial alternating current source for operating said device, said device comprising a core having core elements equipped with coils, a first circuit connectible to said alternating current source and including certain of said coils and rectifier means for supplying rectified alternating current thereto, the inductance of said circuit being sufficiently great to render rectified current substantially continuous, the inductive reactance of said circuit at the frequency of said source being at least four times the direct current resistance thereof, a second circuit including at least certain of said coils and connectible to said alternating current source, the inductive reactance of said second circuit being not more than one-fourth of the inductive reactance of said first circuit, and means for connecting either of said circuits to said alternating current source. 55

12. The method of holding a ferrous work piece on an electromagnetic chuck and subsequently destroying a remanent magnetism that has been induced in said work piece by being 70

75 of said coils and connectible to said alternating

held on said electromagnetic chuck, which method comprises applying unidirectional current to said chuck to hold said work piece thereon, leaving the work piece on said chuck, disconnecting said unidirectional current, then applying to said chuck alternating current at frequencies of the

commercial power supply range and of an effective value to afford an alternating demagnetizing flux in the chuck and work piece, substantially equal to the holding flux resulting from the unidirectional current.

SAMUEL KARASICK.
